MEDICAL TRAY

Michael Taterka, Glendale, Calif., assignor to Pharma-seal Laboratories, Glendale, Calif., a corporation of California

Filed Nov. 13, 1962, Ser. No. 72,455

Term of patent 14 years

(Cl. D83—1)

FIG. 2.

FIG. 3.

FIG. 4.

FIG. 5.

FIG. 6.

FIGURE 1 is a top plan view of a medical tray, showing my new design;

FIGURE 2 is a side elevational view looking from the right side of FIGURE 1;

FIGURE 3 is a sectional view on the line 3—3 of FIGURE 1;

FIGURE 4 is a sectional view on the line 4—4 of FIGURE 1;

FIGURE 5 is a sectional view on the line 5—5 of FIGURE 1;

FIGURE 6 is a side elevational view looking from the left side of FIGURE 1;

FIGURE 7 is a bottom plan view;

FIGURE 8 is a front elevational view; and

FIGURE 9 is a rear elevational view thereof.

The dotted line showing of the manometer, three-way stopcock, syringes, extension tube, needle packages,

ampul, and gauze sponges in FIGURE 1 is for illustrative purposes only.

I claim:

The ornamental design of a medical tray, as shown and described.
